UNITED STATES PATENT OFFICE.

WILLIAM J. FERGUSON, OF BALTIMORE, MD., ASSIGNOR OF TWO-THIRDS
TO J. OLNEY NORRIS AND ISAAC T. NORRIS, BOTH OF SAME PLACE.

GAS-PUMP.

SPECIFICATION forming part of Letters Patent No. 297,773, dated April 29, 1884.

Application filed November 1, 1883. (No model.)

To all whom it may concern:

Be it known that I, WILLIAM J. FERGUSON, a citizen of the United States, residing at Baltimore city, State of Maryland, have invented 5 certain new and useful Improvements in Pumps for Gases, of which the following is a description.

My invention relates to pumps for gases or air, and more particularly to that class of 10 pumps which are employed for changing the tension of a gaseous medium in refrigerating machinery.

The improvements consist in the peculiar construction and arrangement of the piston, 15 which has a valve incorporated in it, and in the means for tightening up the stuffing-box in the lower end of the cylinder, as will be more fully described hereinafter.

The figure is a vertical section of the pump. 20 In the drawing, A represents the cylinder, which stands upright and is supported upon a frame, B. C is the piston, which is made hollow, and has upon its lower end radial arms connecting with a central hub, a, and forming a spider-frame connection for the piston-rod D, which is screwed into this hub and firmly fastened by a pin. In the central upper portion of the piston a funnel-shaped 25 valve, E, is arranged, which is fitted in the piston flush with its upper surface, and has a central aperture that is tightly closed by a cap-plate, b, that is snugly fitted in the top of the valve with a ground joint, and is screwed or otherwise fastened to the same. Both the 30 upper surface of this plate b and the valve E are, when the valve is closed, flush with or in the same plane with the upper surface of the piston. The upper end of the piston-rod, which protrudes through the hub a, is reduced in size 35 and extends loosely through a hole in the lower part of the funnel-shaped valve, and is secured by a nut, c, in the middle of the valve. Just here will be seen the use of cap-plate b, which is to be removed in order to give 40 access to the top of the piston-rod to apply or remove the nut and still preserve a flat flush face for the piston, to permit the latter to close up tightly against the head of the cylinder and expel all the air, as is necessary in all ef-

fective air or gas pumps. The funnel-shaped 50 valve, it will be seen, has a loose up-and-down play on the reduced end of the piston-rod sufficient to allow said valve to open and close on its seat. Gas or air is taken into the cylinder through pipe E², opening into the bottom 55 of the same, and passes up through the piston and its valve, and is expelled through the valve F, whose face is flush with the inner surface of the upper cylinder-head. Thus on the downstroke of the piston gas passes up through 60 the same and lifts its valve, passing to the upper side of the piston and filling the chamber on that side. Then on the upward stroke of the piston the gas is compressed and forced out through the valve F in the top cylinder-head. G is this cylinder-head, which is bolted to the cylinder and is cast with a chamber, e, 65 into which the valve F opens, and from which the compressed gases are carried away through outlet f. The cylinder-head G is formed with 70 a central opening in its top, having flanged edges g, which opening is closed by a flanged cap, H, bolted with a tight joint to the flanges g of the cylinder-head. This cap has a hole 75 in its center to receive and guide the stem of valve F as the latter plays up and down. Above this stem is placed a spiral spring, i, whose tension may be regulated by a tightly-fitted set-screw behind it. At the lower end 80 the cylinder has secured a detachable-head, I, bolted between the flanges of the cylinder and the supporting-frame B, and the supporting-frame has formed with it a downwardly-projecting gland, j, of larger diameter than the piston-rod. In the lower end of this gland, 85 and surrounding the piston-rod, is a tube, k, between which and the cylinder-head there is left a space for stuffing, which may be compressed by the upward movement of the tube k to form a tight stuffing-box for the piston-rod. To force this tube up, I screw-thread the lower exterior portion of the gland j and screw 90 onto it a nut, l, whose lower portion is formed into a ratchet-wheel, m. Around the exterior of this nut there swivels a ring, to which is attached a lever, n, which has a spring-pawl, o, that engages with the ratchet-wheel, so that by oscillating this lever n the ratchet-wheel is 95

turned, the attached nut screwed up, and the tube *k* is pressed more tightly against the packing on the stuffing-box.

Having thus described my invention, what I claim as new is—

1. The combination, with a hollow piston, of a rod secured to one end of the piston and having a headed end wholly within the piston, and an upwardly-opening valve having its upper face flush with the upper end of the piston when said valve is closed, and arranged upon the end of the rod to slide thereon and be guided and limited in its motion, substantially as described.
- 15 2. The combination of the hollow piston *C*, the rod *D*, secured to one end of the piston, and having a headed end, the valve *E*, having

its upper face, when closed, flush with the piston and guided upon the end of the piston-rod, and the detachable plate-cap or plate *b*, secured to the valve flush with the same, as described.

- 20 3. The combination, with the cylinder, its head, and rod *D*, of the frame *B*, having gland *j*, the tube *k*, the nut *l*, provided with ratchet *m*, and a lever bearing a pawl for said ratchet and swiveled upon a support concentric with relation to said ratchet, substantially as and for the purpose described.

WILLIAM J. FERGUSON.
